UNITED STATES PATENT OFFICE

DAVID W. MCPROUD, OF FARMLAND, INDIANA, ASSIGNOR OF ONE-HALF TO THOMAS J. SUMWALT, OF FARMLAND, INDIANA.

POST.

1,033,916.

Specification of Letters Patent. Patented July 30, 1912.

Application filed May 27, 1912. Serial No. 700,061.

To all whom it may concern:

Be it known that I, DAVID W. MCPROUD, a citizen of the United States, residing at Farmland, in the county of Randolph, and 5 State of Indiana, have invented certain new and useful Improvements in Posts, of which the following is a specification, reference being had to the accompanying drawings.

This invention relates to new and useful 10 improvements in fence posts and more particularly to concrete posts, the object of the invention being to provide a novel post of the above character whereby the use of braces above the ground is entirely eliminated.

Another object of the invention is to provide an improved fence post with novel 20 means for anchoring the same in the ground which will save time and labor in digging a pit 5 or 6 feet in the ground for anchoring the various kinds of posts which are in use at the present time.

A further object of the invention is to provide a post of the above character which 25 will possess advantages in points of efficiency and durability, is inexpensive to manufacture and at the same time is simple in construction and operation.

With the above and other objects in view, 30 the invention consists in the novel features of construction and the combination and arrangement of parts hereinafter more fully described, pointed out in the claims, and shown in the accompanying drawings in 35 which,

Figure 1 is a vertical sectional view of my 40 improved post showing the core or filler in elevation. Fig. 2 is a sectional view on the line 2—2 of Fig. 1.

Referring more particularly to the drawings, 1 indicates the base which is of substantially cross shaped and comprises the members 2 and 3 which are interlocked at their intermediate portion as shown at 4 and 45 arranged at right angles to each other.

The numeral 5 indicates the core or filler 50 for the post, having its lower end arranged in the opening 6 which is formed in the intermediate portions of the cross members 2 and 3.

Before the post is set in the ground, the 55 same is securely braced by means of the wire 7, one end of which encircles the post above the cross pin 8 which is arranged transversely through the post at the ground line.

The wire is then passed through the eye 9 on one end of the cross piece 2, then across and in through the eye 10 on one end of the cross piece 3, thence upwardly to a point adjacent the upper end of the post, where the 60 wire makes a half circle of the post and is held in place by means of the cross pin 12 which is arranged transversely through the post. The wire then extends downwardly and out through the eye 13 mounted upon 65 the cross pins 3 opposite the eye 10, the wire then extends inwardly and around the post as shown at 14 and the eye 15 mounted upon the end of the cross pins 2 opposite the eye 9, the wire then extends upwardly and half 70 way around the upper end of the post as shown at 16 and is supported by means of the cross pin 17 arranged transversely through the upper end of the post. After the wire partially encircles the post as shown 75 at 16, it then extends downwardly and in through the eye 9, then extends around the post and out through the eye 10, across and through the eye 15, thence across through the eye 13, and from the eye 13 extends 80 across and through the eye 9 and the extreme end of the wire is then twisted as shown at 18.

The brace wires 19 are drawn closely inward toward the post, at the ground line, by 85 small pieces of wire which are looped around the outer side of the wires and then twisted tightly together as shown at 20 so as to draw the brace wires closely to the post. It will be understood that the post may be set any 90 distance in the ground and the pin 8 is arranged transversely through the post at the ground line. The preferred depth in setting the post in the ground is eighteen 95 inches, after the pit has been dug, the base 1 is set down in the ground and concrete or cement is poured in the pit to fill the same up to the ground line. The brace wires 19 and the core 5 is then inclosed by the cement or concrete, the same being formed of any 100 suitable size and shape desired. The core 5 may be formed of wood, iron or any other suitable material desired.

It will be understood that any suitable 105 fastening means may be employed to secure the fence wires to the post, and it will also be understood that holes may be drilled transversely through the post, before the same has been completed, and running the fence wire through the post, if desired. It 110

will be understood that my improved post is not only applicable for use as a fence post but the same may be used as a telephone, telegraph, or any other pole of this character which requires a substantial base which cannot be easily removed from the ground.

While I have shown and described the preferred form of my invention it will be obvious that various changes in the details 10 of construction and in the proportions may be resorted to for successfully carrying my invention into practice without sacrificing any of the novel features or departing from the scope thereof.

15 What I claim is:—

1. In a device of the character described, the combination of a base comprising cross pieces arranged at right angles to each other, eyes secured to the cross pieces, a post having its lower end mounted in the intermediate portions of the cross pieces, a pin extending transversely through the post adjacent the lower end thereof, pins extending transversely through the upper end of the 25 post and arranged at right angles to each other, brace members comprising a single length of wire having one of its ends encircling the post adjacent the first pin, the other end of said wire passing through the 30 eyes on the base member, extending upwardly and partially encircling the upper end of the post above the cross pins.

2. The combination of a base comprising cross pieces arranged at right angles to each other and interlocked at their intermediate portions, eyes secured to the cross pieces adjacent each end thereof, a post having its lower end mounted in the intermediate portions of the cross pieces, a pin extending 40 transversely through the post adjacent the lower end thereof, pins extending transversely through the post at the upper end thereof and arranged at right angles to each other, a brace wire having one end encircling the post above the first pin, extending 45 downwardly and through an eye on one of the cross pieces, thence across and through

an eye on the other of the cross pieces, thence upwardly and half way around the post above one of the pins at the upper end thereof, thence downwardly and through an eye on the second cross piece, thence extending around the post and through an eye on the first cross piece, thence upwardly and half way around the post above the second pin 50 at the upper end of the post, thence downwardly and through the first eye, then around the post and through the second eye, thence through the fourth, third, and first respectively, and the extreme end of said 60 wire being twisted to securely hold the same against movement.

3. In a device of the character described, the combination of a base comprising cross pieces arranged at right angles to each other and interlocked at their intermediate portions, eyes secured to the cross pieces adjacent each end thereof, a post having its lower end mounted in the intermediate portions of the cross pieces, a pin extending transversely 65 through the post adjacent the lower end thereof, pins extending transversely through the post at the upper end thereof and arranged at right angles to each other, a brace wire having one of its ends encircling the 70 post above the first pin, said brace wire extending through the eyes upon the base member and twice upwardly and half way around the post above the second pins, and then around the post at the lower end and 80 through the eyes, and its other end twisted upon itself to securely hold the same in place, auxiliary wires looped around the upwardly extending wires beneath the first pin to draw the upwardly extending wires inwardly to 85 toward the post, said base, brace wires and post being entirely covered with concrete or cement.

In testimony whereof I hereunto affix my signature in the presence of two witnesses. 90
DAVID W. McPROUD.

Witnesses:

RALPH E. LYST,
JASPER NEWTON FISHER.
